MICRO-PROJECTOR

Charles J. De Grave, Jr., Chili, N. Y., assignor to Bausch & Lomb Optical Company, Rochester,
N. Y., a corporation of New York

Application April 9, 1949, Serial No. 1,890

Term of patent 14 years

(Cl. D57—1)

To all whom it may concern:

Be it known that I, Charles J. De Grave, Jr., a citizen of the United States and a resident of the town of Chili, county of Monroe, and State of New York, have invented a new, original, and ornamental Design for a Micro-Projector, of which the following is a specification, reference being had to the accompanying drawing, forming a part hereof.

Fig. 1 is a front perspective view of a micro-projector, showing my new design with the characteristic features of the design shown in full lines on the drawing.

Fig. 2 is a rear perspective view showing the opposite side of the micro-projector, the broken line showings in Fig. 1 being omitted for convenience of illustration.

I claim:

The ornamental design for a micro-projector, substantially as shown and described.

CHARLES J. DE GRAVE, JR.
